ELEVATOR DOORSTOP

Joseph H. Borden, Philadelphia, Pa., assignor to
 Atlantic Elevator Co., Inc., Philadelphia, Pa., a
 corporation of Pennsylvania

Application November 6, 1939, Serial No. 303,096

3 Claims. (Cl. 16—51)

My invention relates to means for controlling the speed of operation and stopping an elevator door or the like upon opening or closing.

It has been found that the speed of operation of a door may be kept within narrow limits not only during its movement but also during the checking or stopping period by the use of a small, submerged orifice and a graduated needle for controlling the size of and eventually closing the orifice near the end of the stroke.

More specifically, my invention comprises: a sliding door for elevators or the like, a pivotally mounted linkage connected at one end to said door, pistons connected to the opposite end of said linkage, cylinders co-operating with said pistons and containing liquid, a passage for the supply of said liquid to the space between said piston and said cylinder as said piston moves to one end of its stroke, a submerged orifice controlling the escape of liquid from between said piston and said cylinder as said piston moves to the opposite end of its stroke, and a graduated needle controlling the size of said orifice and eventually closing it as said piston moves to the end of its stroke.

For a further exposition of my invention, reference may be had to the annexed drawing and specification at the end thereof my invention will be specifically pointed out and claimed.

In the drawing:

Fig. 1 is a front elevation of my device with parts broken away and with the alternate position shown in dotted lines.

Fig. 2 is a side elevation of the door-checking mechanism shown in the upper part of Fig. 1.

Fig. 3 is a longitudinal cross-section, on an enlarged scale, of the piston and cylinder forming a part of my device.

Fig. 4 is a fragmentary longitudinal cross-section on a still further increased scale showing the piston and cylinder at one end of the stroke.

In that embodiment of my invention chosen from among others for illustration in the drawing and description in the specification my device is shown as consisting of a track or rail 1 on which is mounted a sliding door 2 for an elevator or the like by means of wheels or rollers 3 carried in hangers 4.

Fast to door 2 is a linkage comprising a lever 5 having pivotal connection with a second lever 6 which, in turn, is mounted on a stationary pivot 7 and which carries at its upper end a cross-head 8 of T-shape, which carries at its outer end pins 9 which are pivotally connected with 50

brackets 10 which, in turn, are connected to piston rods 11.

The cylinder and piston mechanism is provided in duplicate so that a description of but one will suffice. Piston rod 11 carries at its inner end a pin 12 to which is attached a piston 13 having a port 14 therein. A plate 15 closes one end of port 14 and is provided with an orifice 16 best seen in Fig. 3 therethrough. Plate 15 has a 10 sliding movement transversely of piston 13 and is yieldingly held against this sliding movement by a spring 17. Piston 13 also has a passage 18 of large size relative to orifice 16 passing therethrough. Passage 18 is controlled by a ball 15 or like valve 19.

Cylinder 20 receives piston 13 slidably therein and is adapted to contain a liquid (omitted from the drawing for the sake of clarity). At one end, cylinder 20 carries a stuffing box generally indicated at 21 and which prevents the leakage around piston rod 11. At its opposite end, cylinder 20 carries a graduated needle 22 detachably mounted in position by means of a support 23 on a yoke 24 carrying a pin 25 by means of which the piston and cylinder mechanism are mounted on a support 26. Cylinder 20 has a filling plug 27 which may be removed to supply or remove liquid to or from cylinder 20. It is preferred to provide liquid in sufficient amount 20 so that orifice 16 is submerged in all positions of the travel of pistons 13.

The operation of my device is as follows. Assuming the device to be in the position shown in full lines in Fig. 1 and to be moved towards the 35 position in dotted lines in Fig. 1, the piston 13 in one of the cylinders 20 is at the upper end of its stroke, while the piston 13 in the other cylinder 20 is at the lower end of its stroke.

Referring now to Fig. 3, if the cylinder 20 is assumed to be the left-hand cylinder in Fig. 1, the piston 13 is moved downward or toward the right as seen in Fig. 3. The ball-valve 19 closes the passage 18 so that the escape of oil from the space between the piston 13 and the yoke 24 is 40 governed by the orifice 16. The size of this orifice can be nicely calculated so that the variation in response to temperature of the discharge from the orifice can be held in very narrow limits. As piston 13 nears the end of its stroke, needle 22 enters orifice 16 in plate 15 and therefore changes the size of this orifice and eventually closes it. The size of orifice 16 is large with respect to the end or point of needle 22 and, because of the sloping sides of needle 22 and the lateral movement of plate 15, the plate 15 is prop- 45

erly centered on the needle 22 so that the needle 22 eventually closes orifice 16. Orifice 16 thus controls the speed of door 2 during its movement and needle 22, by varying the size of orifice 16 and eventually closing it during and at the end of the checking period, brings the door to a smooth, controlled stop. The device operates in the reverse way when the door is moved in the opposite direction. Valve 19 opens to permit a relatively large flow of liquid through passage 18 and hence substantially free movement of piston 13 in cylinder 20.

I do not intend to be limited save as the scope of the prior art and of the attached claims may require.

I claim:

1. An hydraulic control and checking means for elevator and like doors comprising: a cylinder having liquid therein, a yoke closing one end of said cylinder, a piston mounted for travel in said cylinder toward and away from said yoke, provisions constituting a passage for supplying liquid to the space between said piston and said yoke as said piston travels away from said yoke, a disk mounted in said piston for lateral movement and having an orifice therethrough provid-

ing for the escape of liquid from between said piston and said yoke as said piston travels toward said yoke, and a graduated needle co-operating with said piston and arranged to vary the size of and eventually close said orifice as said piston travels closest to said yoke.

2. In a speed controller and check for an elevator door or the like, a cylinder adapted to be mounted adjacent said door, a pair of aligned liquid-containing chambers in said cylinder, said chambers being connected by a bypass of relatively small area and a check valve controlled passage of relatively large area, a disk mounted in said bypass for lateral movement and having a hole therethrough forming the smallest cross-section of said bypass, a piston mounted in said cylinder between said chambers and arranged for connection with said door, and a graduated needle co-operating with said disk and arranged to center the disk thereon and to vary the size of and eventually close said hole as said piston nears the end of its stroke in one direction.

3. In the combination according to claim 2, a spring stressing on said disk and arranged to hold it yieldingly against lateral motion.

JOSEPH H. BORDEN.
